UNITED STATES PATENT OFFICE

168,058

COMBINATION LAMP AND DISPLAY DEVICE

Irving Mark, Chicago, Ill., assignor to Artus D.
De Lano, Battle Creek, Mich.

Application July 30, 1952, Serial No. 20,825

Term of patent 14 years

(Cl. D80—1)

To all whom it may concern:

Be it known that I, Irving Mark, a citizen of the United States, residing at Chicago, Illinois, have invented a new, original, and ornamental Design for a Combination Lamp and Display Device, of which the following is a specification, reference being had to the accompanying drawing, forming a part hereof.

Figure 1 is a front and side perspective view of a combination lamp and display device, showing my new design.

Figure 2 is a rear and side perspective view of the combination shown in Figure 1.

I claim:

The ornamental design for a combination lamp and display device, substantially as shown.

IRVING MARK.
